UNITED STATES PATENT OFFICE.

WALTER S. ADAMS, OF PHILADELPHIA, PENNSYLVANIA, ASSIGNOR TO JOHN A. BRILL, OF SAME PLACE.

DESIGN FOR AN AXLE-BOX FRAME.

SPECIFICATION forming part of Design No. 25,101, dated January 28, 1896.

Application filed January 3, 1894. Serial No. 495,557. Term of patent 14 years.

To all whom it may concern:

Be it known that I, WALTER S. ADAMS, a citizen of the United States, residing at Philadelphia, in the county of Philadelphia and State of Pennsylvania, have invented and produced a new and useful Design for an Axle-Box Frame, of which the following is a specification, reference being had to the accompanying drawings, forming part of the same.

10 My invention has relation to the design for an axle-box frame. The essential feature is its configuration.

15 In the drawings forming part of this specification, Figure 1 is a side elevation, and Fig. 2 a plan view.

20 The axle-box frame is composed of the intermittent side bars, 1, and cross-bars 2, the union of the cross-bars forming a frame continuous in outline and rectangular in shape. The side bars have the central sections, 3, and end sections, 4 5, the end sections 4 lying above the plane of the end sections 5. Intermediate of the ends of the side bars are located the axle-box yokes 6 7, the side bars 25 being intermittent, leaving spaces 8 9 between the intermittent portions, the opposing ends of the side bars having the yokes extending therefrom, which are approximately in the shape of an inverted U. The bearing-surface 10 of the yokes 6 extends above and below the plane of the web of the end sections

4, and the bearing-surface 11 of the yokes 7 extends above and below both the central and end sections 3 5. The central cross end sections 2 3 5 are disposed below the plane of 35 the web of the cross and end sections 2 4, the central sections, 3, joining the inner legs of the yokes 6 near the bottom thereof. Extending outwardly or rearwardly from the top of the yokes 6 are bars 12 flat on top, as 40 in Fig. 2, and the bars 12 are united transversely by a cross-bar 13, Fig. 2.

The side-defining lines of the yokes 7 are parallel, as seen in Fig. 1, and the legs of the yokes 6 are wider than the bars 3 and 4. At 45 the inner corners of the yokes are outwardly-extending projections 14.

By reference to Fig. 2 it will be seen that the yokes 6 7, bars 12 and cross-bar 13 are wider than the side and cross bars of the axle- 50 box frame.

I claim—

The design for an axle-box frame, substantially as herein shown and described.

Signed at New York, in the county of New 55 York and State of New York, this 20th day of December, 1893.

WALTER S. ADAMS.

Witnesses:

B. S. WISE,
JOSEPH L. LEVY.
